SAFETY POLISH ROD STOP

Gould Wells, Gila Bend, Ariz.

Application May 14, 1934, Serial No. 725,525

3 Claims. (Cl. 24—263)

My invention relates to improvements in safety polish rod stops for use on oil or other deep well pumps to prevent damage to the lower pump parts whenever the reciprocating mechanism gives way. This device is not to be confused with sucker rod supports used in handling sucker rods in and out of wells, or with polish rod grips used to connect the walking beam reins to the polish rod.

10 The objects of this invention are first, to provide an easily adjustable stop which may be attached to the polish rod below the polish rod grip and above the lower limit of travel of the rod; second, to provide means whereby the stop will firmly grip and hold the polish rod at a predetermined position whenever the mechanism above the stop gives way. Other objects will appear hereinafter.

20 I accomplish these objects by means of the mechanism and devices illustrated in the accompanying drawing in which—

Figure 1 is a sectional elevation of the complete device in position on a polish rod; Figure 2, a horizontal section of the stop collar taken on line 2—2 Figure 1; Figure 3, a plan view of the spider; Figure 4, a side elevation of a slip, showing the inner face; and Figure 5, a vertical section of the slips. Similar numerals refer to similar parts in all views.

30 All parts of the device, as hereinafter described, are made preferably of steel. The spider 2 is illustrated as resting on the pump-head 3, but it is obvious that the lower part of the spider may be threaded to screw directly into the top of the pump-head. The lower portion of the spider 4 is drilled to receive the polish rod loosely, or with an easy sliding fit, and the upper portion has a tapered opening 6, the sides of which co-operate with taper 7 of slips 8 to form a slip seat.

40 The slips are held in place upon the polish rod by a stop collar 9 surrounding the polish rod and having a cylindrical bore 10 forming an annular cavity into which the upper portions of the slips may be received and retained. These upper portions are shaped so that each has an arcuate periphery adapted to fit within a proportionate part of cavity 10 while their lower portions have a rounding taper 7 adapted to fit into, co-operate with, and substantially conform to the female taper bore or slip seat 6 in the spider. In the aggregate, aside from the inter-spaces 20 to allow for take-up, the upper portions of the slips form a cylinder surrounding the polish rod and conformable to the annular cavity 10 in the stop-

collar, and the lower portions form a segmental slip stop.

Set screws 11 threaded thru stop-collar 9 bear upon slips 8 and firmly clamp them upon the polish rod. Each slip is provided with a drilled cavity 16 of somewhat larger diameter than the end of the set screw operative therein so that when in register the slips will hang in place when the set screws are slightly loosened thus enabling adjustments to be easily made. These cavities are large enough and positioned so that when the stop is actuated the upper ends of the slips bear on the upper domed top 13 of cylindrical cavity 10 and do not tend to shear the ends of the set screws.

15 The groove 17 on the inner face of the slips may be plain or provided with serrations 18 to form wickers as shown particularly in Figure 4. The spider 2 is provided with trunnions 14 to aid in handling the assembly after the stop has actuated and set.

20 In operation the spider is placed upon or attached to the pump-head as above mentioned, and the upper stop collar with the slips in place is secured in position on the polish rod by tightening the set screws 11, above the lower limit of the travel of the rod.

25 The set screws, while exerting considerable force, are not intended to sustain the weight of the polish rod when the device is actuated, but are primarily intended to hold the slips in place and resultantly hold the stop collar in place upon the polish rod.

30 Now, in case any portion of the pumping machinery above the stop gives way, the stop collar and slips drop into position upon and within the spider. This position is indicated by the dotted outline 19, Figure 1. The wedging action of the cooperating tapers forces the slips tightly onto the polish rod and the assembly thus formed holds the polish rod in place above the pump head and prevents it and the attached sucker rods from falling further and damaging the valves and casing of the pump.

35 While I have shown the slips as consisting of two parts only, it is obvious that any plural number may be used, depending on the size of the polish rod and the weight the device is likely to be called upon to sustain. In its preferred form two slips are found to be sufficient to hold any ordinary pumping equipment.

40 After the device has actuated the polish rod is held within the spider and the latter rests upon the pump head, or its mechanical equivalent, depending on the set-up. With the rod held in this

45 50 55

manner repairs can be made and then reins may be attached to the trunnions 14 and the assembly, including the polish rod itself, raised to operative position.

5 I claim:—

1. A well pump polish rod safety stop comprising, in combination, a spider adapted to rest on the pump head having a downwardly diminishing taper bore to form a slip seat, a stop collar provided with a downwardly facing cavity adapted to receive the upper ends of a plurality of slips, means for retaining the upper portions of said slips within said cavity and positioning said collar upon the polish rod above said spider, and a plurality of slips surrounding the said polish rod having the upper portions shaped to fit within the cavity in said stop collar and be retained therein.
2. A well pump polish rod safety stop comprising, in combination, a spider adapted to rest on the pump head, having a downwardly diminishing taper bore forming a slip seat, a stop collar positioned on the polish rod above said spider having an upwardly extending annular cavity adapted to

receive the upper portions of a plurality of slips, means for retaining said slips within said annular cavity, a plurality of slips having their upper portions rounded to fit within the cylindrical cavity in said stop collar and be retained therein, whereby said stop collar is positioned upon the polish rod.

3. A well pump polish rod safety stop, comprising in combination, a spider adapted to rest on the pump head having a downwardly diminishing taper bore forming a slip seat, a stop collar adapted to be positioned on the polish rod above said spider having an upwardly extending cylindrical bore forming an annular cavity around the polish rod and terminating upwardly with a domed top face, set screws radially positioned in the sides of said stop collar and adapted to bear upon the upper portions of slips fitting within said annular cavity, a plurality of slips surrounding said polish rod having recesses adapted to receive the inner ends of the said set screws but having a larger diameter, whereby adjustment of said slips on said polish rod is facilitated.
